US00D787480S

(12) **United States Design Patent** (10) **Patent No.:** **US D787,480 S**
(45) **Date of Patent:** **** May 23, 2017**

(54) **PAIR OF EARBUD TIPS**

(71) Applicant: **Oculus VR, LLC**, Menlo Park, CA (US)

(72) Inventors: **Quintin Morris**, Issaquah, WA (US); **James Stocker Webb**, Seattle, WA (US); **Mark Shintaro Ando**, Seattle, WA (US); **Peter Wesley Bristol**, Seattle, WA (US); **David Tao**, Santa Clara, CA (US)

(73) Assignee: **Oculus VR, LLC**, Menlo Park, CA (US)

(**) Term: **15 Years**

(21) Appl. No.: **29/550,149**

(22) Filed: **Dec. 30, 2015**

(51) LOC (10) Cl. **14-01**

(52) U.S. Cl.

USPC **D14/223**

(58) **Field of Classification Search**

USPC D14/223; D24/174; 181/129, 130, 135; 379/430, 431; 381/322, 325, 328, 330, 381/372, 380, 381, 72, 311, 324, 371, 381/313; 455/90.3, 575.1

CPC H04R 1/10; H04R 25/00; H04R 25/02; H04R 1/1016

See application file for complete search history.

(57) **CLAIM**

The ornamental design for a pair of earbud tips, as shown and described.

DESCRIPTION

FIG. 1 is a front isometric view of a left one of a pair of earbud tips showing the new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a front isometric view of a right one of the pair of earbud tips showing the new design.

FIG. 9 is a front elevation view thereof.

FIG. 10 is a rear elevation view thereof.

FIG. 11 is a left side elevation view thereof.

FIG. 12 is a right side elevation view thereof.

FIG. 13 is a top plan view thereof; and,

FIG. 14 is a bottom plan view thereof.

The broken lines depict environment that forms no part of the claimed design.

1 Claim, 14 Drawing Sheets
